Inventor,

John M. Taber.

UNITED STATES PATENT OFFICE.

JOHN M. TABER, OF GREENWICH, NEW YORK.

IMPROVEMENT IN HAY-ELEVATORS.

Specification forming part of Letters Patent No. 35,045, dated April 22, 1862.

To all whom it may concern:

Be it known that I, JOHN M. TABER, of the town of Greenwich, in the county of Washington and State of New York, have invented a new and Improved Hay-Elevator; and I do hereby declare the following to be a full, clear, and exact description of my invention, reference being had to the accompanying drawings, forming a part of this specification.

Like letters in said drawings refer to like parts.

Figure 1 is a perspective view of my elevator ready for use. Fig. 2 shows an elevation of the same as it appears after the contents have been discharged.

My hay-elevator, as represented in Figs. 1 and 2, consists of two gang-forks, A A', united at their upper extremities by a joint, K, thus forming a head. To this head is attached a ring, C, through which pass the ropes E and F. The rope E passes under the sheave a in the block G, and is fastened to the gang-fork A' at the staple or ring g. The rope or chain F passes down under a pulley, i, Fig. 2, attached to the fork A', and is fastened to a pin, b, in the block G. These two ropes or chains are joined at a point above and form the single rope B, which rope passes up over a pulley above for the purpose of raising the elevator. The tines of the two gang-forks A and A' are prevented from coming in collision by means of the spring D.

When the elevator is in use the block G is attached to the fork A by means of the bar c in the block G, and is held in place by the hook

d and the trip-latch e. To this latch is attached a cord, H, which passes over a pulley, m, in the gang-fork A', and is used by the operator for the purpose of detaching the block G from the hook d and allowing the two gang-forks to spread asunder, thus disengaging the load. To prepare the elevator for another operation, all that is necessary is to fasten the block G in the hook d. The cord I is attached to the elevator at the point o for the purpose of managing and controlling the same after the desired elevation has been attained.

The advantages claimed for this elevator over others are, first, the joining of the two forks at the head K, so as to avoid collision with adjacent obstacles in its ascent; second, by the process here adopted of attaching the ropes E and F beneath the head or joint K the gravity of the load operates to bring the two forks more firmly together; third, the facility of discharging its contents by the arrangement of means here employed.

What I claim as my invention, and desire to secure by Letters Patent, is—

The combination of the gang-forks A A', united, as described, with the block G, and ropes or chains E and F, in the manner and for the purpose specified.

In testimony whereof I have, on this 18th day of December, 1861, set my hand.

JOHN M. TABER.
